GASHOLDER

John A. Mason, Baltimore, Md., assignor, by
mesne assignments, to Koppers Company, a
corporation of Delaware

Application June 30, 1932, Serial No. 620,244

25 Claims. (Cl. 48—174)

This invention pertains to gas holders and more particularly to that type commonly known as waterless holders. Such type of holders are shown in Letters Patent to Jagschitz Number 1,275,696, dated August 13, 1918.

In commercial practice, where a liquid sealing medium is employed for the piston-like closure of the holder, it is common to have a plurality of so-called skimmer tanks, pumps, and accessory devices located around and about the base of the holder shell in addition to various pipes leading from the pumps to the upper portion of the holder. So too, where the holder body or shell embodies vertically disposed columns which extend inwardly of the shell it becomes necessary to employ special sealing means between them and the piston closure. Again, means is provided, especially in large holders, to prevent the sealing liquid from flowing around in the usual trough or gutter surrounding the closure to one side thereof. Guiding rollers are also commonly employed.

With the present invention a number of outside tanks may be done away with, as well as corresponding pumps and pipes, and in place thereof there is mounted upon the piston-like closure a centrally disposed reservoir or tank from which the sealing fluid passes to the trough or gutter. Such tank, together with the liquid therein acts in a measure, at least, to weight the piston.

Temperature changes have a marked effect upon a holder and the sealing medium. Where the sealing fluid, such as tar, is fed, as at present, to the upper end of the shell and flows down the inner face thereof the tar will have a tendency to congeal or stiffen, if the surface is cold, whereas if the surface is hot, the light oils of the tar will be driven off. So too, the tar within the trough is subject to variations in temperature at different points or areas in the circumference of the tank.

By the employment of a tank as above specified, from which pipes or conduits extend to the gutter or trough which surrounds the piston, the bulk of the sealing liquid is held in storage, so to speak, remote from the walls of the shell and is, therefore, not subject to the temperature variations which exist throughout the wall of the shell or at different portions thereof. This is particularly advantageous in holders of large diameter where the sun acting upon one side will raise the temperature on that side much higher than that which obtains on the side away from the sun.

Furthermore, by connecting the centrally dis-

posed reservoir with the trough by a plurality of pipes a flow of sealing liquid will obtain around the trough and through the pipes, thereby having a tendency to equalize the temperature of the sealing liquid throughout the system.

Instead of employing shell-columns, guiding rollers, and the like, to maintain the piston-like closure in centralized position with reference to the shell and to prevent tipping or canting thereof, there are present one or more vertically disposed guiding columns which pass through suitable bearings or guideways carried by the piston. Again, the sealing liquid is pumped to the upper portion of the holder and distributed upon the upper part of a vertically disposed column; flowing downward thereover; lubricating the same, and the cooperative sealing means carried by the piston; and finally flowing into the centrally disposed tank or reservoir from which it flows outwardly to the surrounding gutter or trough.

With these and other objects in view, reference will be had to the accompanying drawings wherein:

Fig. 1 is a vertical sectional elevation of a portion of a gas holder embodying my invention;

Fig. 2, an enlarged horizontal sectional view of a portion of the holder showing the sealing means and allied parts, the section being taken on the line II—II of Figure 1;

Fig. 3, a vertical sectional view taken on the line III—III of Fig. 2;

Fig. 4, a perspective view illustrating the trough construction which encircles the piston closure and the allied rubbing bars;

Fig. 5, a transverse vertical sectional view illustrative of the manner in which the trough is formed;

Fig. 6, a perspective view of the adjacent ends of two of the rubbing bars;

Fig. 7, a perspective view of two of the elements which enter into the trough construction;

Fig. 8, a vertical sectional view on an enlarged scale showing the centrally disposed column, the centrally disposed tank, the guiding and sealing means employed between the column and the various surrounding elements, and likewise the means for causing the sealing liquid which passes downwardly over the outer surface of the guiding column to be gathered and finally passed to the centrally disposed tank or reservoir;

Fig. 9, a vertical sectional view of the upper distributor employed for receiving the sealing liquid and directing it onto the outer surface of the guiding column;

Fig. 10, a horizontal sectional view taken on the line X—X of Fig. 9;

Fig. 11, a perspective view of a portion of the shell, the piston, the trough, a portion of the rubbing bars, and the means employed for preventing relative rotative movement of said bars with reference to the piston and trough;

Fig. 12, a detail perspective view with parts broken away showing one manner of forming the shell of the holder;

Fig. 13, a perspective view of a portion of the means employed to prevent relative rotative movement of the rubbing bars with reference to the piston; and

Fig. 14, a horizontal sectional view showing a plurality of fixed guiding elements associated with the piston closure, the latter being broken away.

In the drawings (Figs. 1 to 13), 10 denotes the shell of the holder as a whole, the shell being circular in cross section and preferably produced from a plurality of plates welded or riveted together and likewise secured to a plurality of vertical columns. Such a structure is best shown in Figs. 11 and 12 wherein 11 indicates the plates, each of which is provided at its upper and lower ends with outwardly extending flanges 12 and 13. The upper flange 12 of each plate is preferably wider than the lower flange 13 and both of said flanges terminate short of the side edges of the plates so as to permit the plates to pass over and against the inner face of vertically disposed columns 14 and the vertical or side edges of the plates to abut or stand in close spaced relation.

The plates are curved to such a radius that when assembled they will produce a shell of the desired diameter. The upper and lower portion of the body of each plate, where it merges into the flanges 12 and 13, is slightly rounded,—the purpose of which will presently appear.

The plates are temporarily secured to each other, and to the inner flange of the I-beam columns 14, by rivets 15 widely spaced as shown in Figs. 11, 12 and 2 and the various parts are electrically welded along and about the various edges or marginal portions and along the joints produced by the adjacent curved or rounded portions just mentioned, the welding being denoted generally by 16. By the construction thus described there will be produced on the inner face of the shell a series of seams, as at 17, extending entirely around the shell. The surface of these seams may be depressed slightly with reference to the inner face of the shell by proper manipulation of the welding apparatus. These depressions coact with the sealing means and the liquid sealing medium to properly lubricate the inner face of the shell in a manner shortly to be described.

The provision of the flanges 12 and 13 on the plates, and making the former wider and longer, facilitates the welding of such parts. So too, the flanges, in addition to facilitating the jointure of the plates, materially strengthen the shell as a whole as they produce in effect a series of spaced ribs which extend circumferentially of the exterior of the shell, interrupted only by the vertical column 14, while the construction of the shell, as above described, has been found advantageous, still the invention is not limited thereto as any shell which is circular in cross section may be utilized.

The piston closure may be said to comprise a main body 18 having a centrally disposed tank or reservoir 19 while at the outer edge of the

main body 18 there is secured a downwardly extending plate 20, which at its lower portion is curved outwardly, forming a shelf-like member 21.

Suitable angle irons 22 (see more particularly Fig. 11) are embodied in the upper portion of the piston-like structure and serve to stiffen the same. Structural elements, shown in the present instance as I beams denoted by 23, are secured to the elements 20 and extend downwardly below the shelf 21, the lower ends thereof serving as legs to properly support the piston when in its lowermost position, as shown in Fig. 1.

A pair of inclined braces 24 and 25 extend downwardly from the head of the piston, and preferably from beneath the elements 22, and at their lower ends extend outwardly and beneath the shelf-like member 21.

An angle plate 26 is secured to the shelf-like member 21 and likewise to the member 20 where these parts merge into one another and a similar angle plate 27 is secured to the braces 24, 25 and to the adjacent flanges of the vertically disposed I beam 23. This arrangement produces a rigid structure throughout, affording sufficient stability to the piston and to the outwardly extending shelf 21. It will of course be appreciated that any suitable bracing may be employed for the piston-like closure.

The shelf-like element 21 is designed to form one portion of the bottom of a trough which extends circumferentially of the piston and is connected to the reservoir 19 by a plurality of pipes 9. These pipes extend from the lower portion of the reservoir 19 and consequently the sealing liquid within the trough will always be maintained at the same level as the liquid in the reservoir.

Secured to the under face of the shelf 21 (see Fig. 5), and adjacent the outer edge thereof, is an angle plate 28. To the upper face of the shelf 21, and inward of the edge thereof, there is secured an angle plate 29 to the upper portion of which there is attached the inner portion of a flexible fabric member 30. This member overlies a wooden element 31 secured to the upper face of the shelf 21, the member 31 supporting a portion of the member 30 which directly overlies the same and holds it out of contact with the metal shelf 21 which might otherwise tend to abrade it as relative movement takes place between the parts in the up and down movement of the piston. As above noted, the member 30, together with the shelf 21 and upstanding member 20 formed a trough for the reception of the sealing liquid and as a consequence the outer portion of the fabric member 30 extends upwardly and is secured in the following manner to a sectional rubbing bar 32.

The fabric at its upper edge is folded upon itself and over a flange 33 extending upwardly from a rounded body 34, the parts being formed from sheet metal bent to form, as best shown in Fig. 7.

A plate 35 is secured against the downturned upper portion of the fabric. The parts are held in place by bolts which pass through the rubbing bar, the fabric, the upstanding flange 33 and the plate 35. In certain instances where parts of the mechanism employed to move the rubbing bar 32 outwardly into facewise contact with the inner face of the shell are present, the bolts likewise pass through such elements. One of such elements, or a bracket 36, is shown in Fig. 5 with the securing bolt passing through all of

the elements, including the bracket. The bracket also has additional bolts extending therethrough and through the rubbing bar 32 and likewise through spacer blocks 37 interposed between the bracket and the rubbing bar. In this way a gutter is formed by the downwardly extending element 20 and the flexible fabric member 30. The member 34, of which there will be a continuous series around the rubbing bars, will hold the fabric out of contact with the inner face of the shell as well as out of contact with the rubbing bar so that it will not be subjected to wear and will last almost indefinitely.

The rubbing bars 32 are so contoured and of such length as to make a close fit with the interior surface of the shell. Each bar at one end is provided with projections 38, 39 (see more particularly Figs. 4 and 6) thus producing an intermediate space or recess 40, the latter being of such size as to receive a tongue 41 upon the opposite end of an adjacent bar.

The vertical edges of the rubbing bars are beveled or inclined, the inclination of the bevel of the tongue preferably being the reverse of the inclination on the end faces of the projections 38 and 39. The complementary faces upon the various bars are of course reversely inclined so that as the ends of the bars come together a slight wedging action is produced. To maintain the ends of the bars in proper alignment, one of the sections may be provided with a pair of outwardly extending lugs or fingers 42 and 43 which cooperate with suitable retaining blocks 44 and 45.

The elements or brackets 36 are arranged in pairs around and about the structure. Each bracket is provided in the upper portion thereof with an arcuate slot 46 (see Fig. 4). Into each of said slots extends a bar or rod 47 carried by a lever 48 fulcrumed upon a shaft 49 mounted in the brackets 36. The levers 48 at their upper ends extend rearwardly and are provided with adjustable weights 50. The levers 48 are arranged in pairs (see Fig. 2) and are interconnected by a rod or bar 51 which finds its bearings in the lower end of brackets 52 secured to and extending downwardly and outwardly from the upper portion of the piston. These weighted levers, acting through the brackets, force the rubbing bars outwardly into close facewise contact with the inner face of the shell and tend to hold them in such position at all times.

In order to prevent relative rotative movement of the piston with reference to the rubbing bars and the placing of undue strain upon the fabric 30, means is provided for holding the rubbing bars against such relative movement with reference to the piston. To this end there is secured to the rubbing bar a block 53 having an outwardly projecting stud or finger 54 (see more particularly Figs. 3, 11 and 13). Secured to the downwardly extending element 20 of the piston and opposite the block 53 is an angle iron 55 which forms the support for a channel-shaped bracket 56 (see more particularly Figs. 3 and 11), in the outer end of which is mounted a shaft or rod 57. Said shaft forms the support for a weighted lever 58, the lower arm 59 whereof is bent inwardly and secured to a spacer block 60 and an arm 61 likewise fulcrumed upon or attached to the shaft 57. The lower end of the arms 59 and 61 are spaced apart by the block 60 a distance sufficient to permit them to straddle and embrace the stud 54. The inner edges adjacent the lower ends of each of the arms 59 and 61 will be slightly in-

clined so that the arms will have a fair bearing against the block 53.

Inasmuch as the bracket 56 and the allied parts are quite substantial and rigid, the bearings for the lever and the arm 61 are widely spaced apart, and the arms 59, 61 have but slight clearance with reference to the stud or finger 54, relative movement of the rubbing bar and its allied elements with reference to the piston is precluded. The structure also assists in forcing the rubbing bar into contact with the shell.

The centrally disposed tank or reservoir 19, heretofore referred to, is preferably located below the main structure or body of the piston 18. Extending from the foundation of the holder upwardly to the roof structure, which latter is designated generally by 62, and secured to the beams thereof, is a vertically disposed column 63. This column is designed to guide and centralize the piston with reference to the shell. It becomes essential, of course, to seal said piston with reference to the column and to that end liquid sealing means is employed.

Mounted centrally of the tank and extending downwardly therethrough is an annular sleeve 25 or cylinder 64, open at its lower end and adapted, when the piston is in its lowermost position and supported upon the I beams 23 as in Fig. 1, to form a dip seal with the liquid within the reservoir 65 located immediately below the member 64. The reservoir 65 is connected by a plurality of pipes 66 (Fig. 1) with an annular gutter 67 which extends around the base of the holder within the shell.

The member 64 has a collar 68 secured to its upper end, which latter is bolted to a flange 69 extending outwardly from a sleeve 70. The bolts for securing the parts together also pass through laterally extending flanges 71 of the beams 22 heretofore referred to.

Mounted and held within the lower end of the sleeve 70 by welding is a cast steel ring 72, the interior face whereof is grooved, the face having slight clearance with reference to the column 63.

Mounted within the upper portion of the sleeve 70 above the ring is an annular rubbing shoe 73 preferably made up of segmental pieces and held in place by a packing ring 74 having an upwardly extending annular member 75 in which are mounted a plurality of packing rings 76 held in place by a gland 77. The ring 74, as will be seen upon reference to Fig. 8, is drawn to position with reference to the shoe 73 by bolts 78 which extend through a flange projecting outwardly from the ring and through a similar flange 79 formed on the upper part of the member 70.

Mounted upon the member 79 is a tank 80 designed to be filled with sealing liquid. An overflow pipe 81 extends from the upper portion of this tank and terminates in the main supply tank 19. Located above the tank 80 is a cup 82 which receives the sealing liquid which passes downwardly over the outer surface of the column 63. Said cup is attached to and supported by a sleeve 83 or cylindrical element 83 which in turn is secured to various bracing elements 84 forming a part of the bracing for the piston roof.

Within the cylindrical element 83 is mounted a sealing ring 85 similar to the ring 72 and similarly grooved. Located above it is a rubbing shoe 86 similar in construction to the shoe 73 heretofore referred to. A retaining ring or flange 87 is employed to hold the shoe 86 in place. An overflow pipe, the upper end of which termi-

nates at a level somewhat above the ring 87, extends from the cup 82 into tank 80.

The structure just described, to wit, the members 70, 73, 74 and 75, form one bearing for the 5 piston; while the members 85, 86 and 87 form a second bearing. These bearings stand in spaced relation vertically of each other, and tend to prevent tipping or canting of the piston except to a slight degree.

10 Suspended from the roof structure is a receptacle 88, shown as annular in outline, provided with an upstanding collar 89 spaced away from the exterior of the column 63 (see more particularly Fig. 9). The collar 89 is provided, adjacent its lower end, with a series of openings 90 and the lower wall of the receptacle 88 is also provided with a series of openings 91, which latter, conjointly with the openings 90, allow the sealing liquid to pass from the receptacle 88 onto 15 the exterior of the column.

15 Overflow pipes 92 extend through the bottom of the receptacle and are inclined so that their lower open ends will discharge any sealing liquid 20 passing therethrough directly onto the column 25 63.

Sealing liquid is, as is usual, pumped from a 30 tank or reservoir, indicated by 93 (Fig. 1), and passes upwardly through a pipe 94 into a lateral 35 95 which terminates in a short section 96. This section discharges into the receptacle 88. The 40 pump (not shown) will of course only be operated for a period of time sufficient to fill the cup 82, the tank 80, the main reservoir or tank 19, and the gutter surrounding the piston. It will then be stopped until the level of the sealing liquid within the reservoir 19, and consequently in the gutter, falls below a point where the liquid will not longer function with the rubbing bars, at which time the pump will of course have to 45 be again brought into operation.

45 The rubbing bars will of course function with the sealing liquid to effectively seal the piston against the escape of gas around the circumference of the piston. The various sealing elements heretofore described for effecting a gas-tight joint between the centrally disposed guiding column and the piston will prevent escape of gas at this point.

50 It is to be noted that by the use of the tank 80 and the cup 82 separate bodies of liquid are always maintained in direct contact with the column and the packing elements associated with said tank and cup are in a sense submerged within the sealing liquid.

55 While the sealing elements for effecting a tight joint between the column and piston have been described somewhat in detail, it is not intended thereby to limit the invention to any such structure but to include broadly any sealing means, and primarily liquid sealing means, between the piston and column.

Sealing liquid will of course, as in the Jagschitz 60 patent heretofore referred to, seep down between the rubbing shoes or bars and the inner face of the shell and will find its way into the gutter 67 and ultimately, through the pipes 66, into the reservoir 65. When the piston is lowered the lower end of the cylindrical member 64 will pass 65 into the liquid and form a gas-tight seal there-

70 In practice the sealing liquid, such as tar, will be drawn off from the gutter 67 through suitable offtake devices which form no part of the present invention and which are shown diagrammatically 75 and designated by 97 (Fig. 1).

As heretofore noted, the sleeve or cylinder-like member 64 which extends downwardly below the bottom of the piston-like closure, dips into sealing liquid in the centrally disposed fixed reservoir 65, and is in communication through the pipes 66 5 with the gutter 67. When, as in Fig. 1, the piston is in its lowermost position and comes to rest upon the I-beams or legs 23, the lower end of the element 64 passes into the liquid in sealing relation therewith. As a consequence, no gas can 10 pass upwardly around the column nor around the edge of the piston, and workmen are free to move over the upper surface or elements of the piston-like closure and readjust or repair the vertically separated bearing members, heretofore described. 15

In fact, there is no necessity of evacuating the gas which may be entrapped below the piston when it comes to its lowermost position; a condition which so far as I am aware is not true of any other holder. Such evacuation frequently 20 takes considerable time, and as will be readily appreciated by those skilled in the art, an admixture of air and gas below the piston is a dangerous condition.

It is thought that from the foregoing the operation of the structure will be readily understood but a brief résumé may be given. Initially, sealing liquid will be forced through the pipe 94, 95 into the receptacle 88, passing downwardly over the exterior of the column into the cup 82. The column is thus lubricated and the sealing liquid, after filling the cup to the desired degree, will pass into the sealing tank 80 from which it will ultimately flow into the main reservoir or tank 19. From this it flows through the pipes 9 into the gutter and when the desired level is reached, which may be readily determined by a suitable indicating mechanism (not shown), the pump is stopped. Inasmuch as the bulk of the liquid in the reservoir 19 stands at a level above the upper edge of the rubbing bars or shoes, the gutter will be maintained sufficiently full to function with said rubbing bars or shoes for a considerable period of time and, as previously noted, this does away with the frequent stopping and starting of the pumps as in prior structures.

As the piston moves upwardly and over the seams formed between the edges of the plates, a certain amount of the sealing liquid (tar, heavy oil, and the like) will be entrapped and, as a consequence, when the rubbing bars pass the seam the entrapped liquid will be released and will flow down the inner face of the shell. In this way the inner surface of the shell may be said to be lubricated, which of course assists the free movement of the piston in its descent.

While the construction employing the column and reservoir or storage tank has been described in some detail, it is to be understood that in its generic sense the invention is not limited thereto. Thus, for instance, it is conceivable that a large storage reservoir may be mounted upon or built into the piston closure and employed to supply the gutter with sealing fluid;—and this without the necessity of the central guiding column. In other words, such a centralized reservoir could, with advantage, be employed with structures such as shown in the patent to Jagschitz above mentioned,—the tank being recharged from time to time as occasion required. It would of course 70 do away with the draw-backs that inhere with the discharge of the sealing liquid or fluid directly onto the shell as well as other disadvantages.

Instead of a single centrally disposed column 75

a plurality of guiding columns may be employed. Thus, in Fig. 14 three columns 63^a, 63^b and 63^c are shown as extending upwardly through a tank 19^a carried by the piston closure. Said columns 5 will of course have the necessary sealing means associated therewith.

This application is a continuation in part of my application filed October 9, 1931, Serial No. 567,946.

10 What is claimed is:

1. In a waterless gas holder, the combination of a shell; a piston-like closure therein; at least one vertically disposed column located within the shell and extending through the closure, said 15 column serving to guide and stabilize the closure in its movements; a reservoir carried by the closure for storing a liquid sealing medium; sealing means between the column and closure; sealing means between the closure and the inner 20 surface of the shell; and means connecting the reservoir with said last named sealing means, said reservoir and sealing means being so positioned with reference to each other as to maintain a common level of the sealing medium 25 therein.

2. A gas holder as set forth in claim 1 wherein the last named sealing means includes a series of rubbing bars contacting the inner face of the shell; and a gutter for the sealing liquid located 30 intermediate the closure and the bars.

3. In a waterless gas holder, the combination of a shell; a substantially non-yielding or rigid piston-like closure therefor; a rigid column extending upward through the piston; guiding and 35 sealing means coaxing with the column and carried by the closure at its upper side; means involving the use of a liquid for sealing the piston with reference to the shell and to the column; and means for feeding such liquid to the 40 column and for causing it to pass to the above-specified sealing means.

4. In a waterless gas holder, the combination of a shell; a piston-like closure therefor; a series of rubbing bars; a gutter interposed between said 45 bars and said closure and connected thereto; means for forcing the bars outwardly into face-wise contact with the shell; a rigid column extending upwardly through the piston; a reservoir for sealing liquid located centrally of the 50 piston, said reservoir being located in substantially the same horizontal plane as that of the gutter; at least one conduit extending from said reservoir outwardly and opening into the gutter; and means for effecting a gas-tight seal between 55 the piston and the column.

5. In a waterless gas holder, the combination of a shell; a piston-like closure therefor; a rigid column extending upwardly through the piston; a reservoir located centrally of the piston and 60 surrounding the column; means carried by the piston for producing a gas-tight joint between the same and the column; means involving the use of a liquid for sealing the piston with reference to the shell; means extending from the reservoir to said last named sealing means; and means for pumping a sealing fluid to the upper portion of the shell and causing it to flow onto the exterior of the column.

6. In a waterless gas holder, the combination 70 with a cylindrical shell; a piston-like closure therefor; sealing means interposed between the piston and the inner face of the shell; and means acting independently of the sealing means for preventing rotative movement of the sealing means with reference to the piston, whereby the 75

piston and sealing means will be caused to move in unison upon rotative movement of said parts within the shell and the sealing means held against distortion.

7. In a waterless gas holder, the combination 5 of a shell; a piston-like closure therefor; a rubbing bar; means for urging said rubbing bar outwardly into facewise contact with the inner face of the shell; a fabric member secured to said bar and likewise secured to the piston and thereby 10 forming a gutter in conjunction with said bar and piston; a plurality of rounded bodies having upwardly extending flanges, over which flanges the adjacent edge of the fabric member is folded; and means for securing said members to the rubbing bar, whereby the fabric member will be held 15 out of contact with the shell.

8. In a waterless gas holder, the combination of a shell; a piston-like closure therefor; a rubbing bar located outwardly of the piston; means 20 for forcing said bar against the inner face of the shell; a gutter interposed between the bar and the circumference of the piston; a reservoir carried at the center of the piston; a fixed column extending upwardly through the shell and 25 through the piston; a sleeve extending downwardly through the reservoir and sealed with reference thereto and standing in spaced relation to the column; a tank located above the piston; packing submerged within the tank and coaxing 30 with the column; an overflow pipe extending from said tank to the reservoir; a cup located above the tank and surrounding the column; packing carried by said cup and coaxing with the column; an overflow pipe extending from the cup to the 35 tank; means for supplying a sealing liquid to the outer face of the column at its upper end; and at least one pipe extending from the lower portion of the reservoir outwardly to and communicating with the gutter. 40

9. In a waterless gas holder, the combination of a shell; a piston-like closure mounted therein; means for sealing said piston with reference to the shell; a vertically disposed column extending upwardly through the piston; means for securing 45 a gas-tight seal between the piston and the column; a sleeve extending downwardly below the piston, said sleeve standing in spaced relation to the column; a gutter extending around the base of the shell; a reservoir located at the 50 center of the holder and into which the sleeve may pass when the piston is in its lowermost position; and at least one conduit connecting the gutter and the reservoir.

10. In a waterless gas holder, the combination of a shell; a piston-like closure therefor; a storage tank for a fluent sealing medium located centrally of said closure; sealing means interposed between the closure and the inner face of the shell and involving the presence of such fluent sealing medium to render it effective, said tank and sealing means lying in a common plane; and at least one conduit extending from the tank to said sealing means, whereby a relatively large 60 reserve body of fluent sealing medium is maintained within the holder and frequent renewals thereof are avoided.

11. In a waterless gas holder, the combination of a shell; a piston-like closure mounted within the shell; a column extending vertically within 70 the shell and through the piston-like member; vertically spaced bearings carried by the piston-like member, said bearings contacting the column at separated points above the piston-like member and serving to stabilize the piston within the 75

- shell; sealing means interposed between the shell and the edge of the piston, said means being provided with pressure-devices positively impelling the sealing periphery of the closure into contact with the inner wall of the shell and acting independently of the main body of the piston-like closure; and means for feeding a sealing medium to the bearings aforesaid and to the sealing means between the piston and the shell.
- 5 12. In a waterless gas holder, the combination of a shell; a piston-like closure mounted within the shell; a column extending vertically within the shell and through the piston-like member; a plurality of vertically spaced bearings carried by the piston-like member above the same, said bearings contacting the column at separated points, and the lowermost bearing being a combined gas-seal and guide; sealing means interposed between the shell and the edge of the piston 10 ton; and means for lubricating the bearings, and likewise lubricating the sealing means for the piston-like member and shell.
- 10 13. In a waterless gas holder, the combination of a shell; a piston-like closure therefor; a reservoir for sealing material located centrally of the piston-like closure; a column extending upwardly through the holder and passing through the reservoir; means for placing the fluid sealing medium upon the upper portion of the column; sealing means surrounding the piston-like closure; and means extending from the reservoir to said last-named sealing means, to conduct the sealing fluid thereto.
- 15 14. In a waterless gas holder, the combination of a shell; a piston-like closure mounted within the shell and free to move up and down according to the pressure of the gas beneath the same; a column extending vertically within the shell and through the piston-like member; means for sealing the piston-like closure against the escape of gas with reference to the shell; means for placing the fluid sealing medium upon the upper portion of the column; and a bearing carried by the piston-like member and cooperating with the column, said bearing being located above the upper face of the piston-like closure and sealed against the passage of gas by the fluid sealing medium.
- 20 15. A gas holder as set forth in claim 14, wherein in a reservoir is placed centrally of the piston-like member, said reservoir being substantially on a level with the sealing means for the piston and communicating therewith through at least one pipe or conduit.
- 25 16. In a waterless gas holder, in combination: an outer shell enclosing the gas-space; a rigid center column extending from the base of the holder to the top thereof; a rigid piston-like closure structure covering the gas-space and adapted to rise and fall in sealed gas-tight relation with the outer shell and the center-column; and vertically disposed guide-members adapted to maintain the substantial horizontality and equilibrium of the closure structure and to guide it upon and support it in respect of the center-column and independently of the shell, said guide-members being located outside of and above the gas-space and accessible from the upper side of the closure structure without communication with the gas-space, and the lower one of said guide-members being a combined gas-seal and guide; the sealing means between the closure structure and the shell and column comprising substantially continuous contact members and a mobile sealing medium and means for supplying such medium at the sliding surfaces of the closure structure.
- 30 17. In a waterless gas holder, in combination: an outer shell enclosing the gas-space; a center column; a piston-like closure structure covering the gas-space and adapted to rise and fall in sealed gas-tight relation with the outer shell and the center-column; vertically disposed guide-members adapted to maintain the substantial horizontality and equilibrium of the closure structure and to guide it upon and support it in respect of the center column and independently of the shell, said guide-members being located outside of and above the gas-space and accessible from the upper side of the closure structure without communication with the gas-space; the sealing means between the closure structure and the shell and column comprising substantially continuous contact members and a mobile sealing medium and means for supplying such medium at the sliding surfaces of the closure structure; and means for lubricating the piston-like closure.
- 35 18. In a waterless gas-holder, in combination: an outer shell enclosing the gas-space; a center column; a piston-like closure structure covering the gas-space and adapted to rise and fall in sealed gas-tight relation with the outer shell and the center-column; vertically disposed guide-members adapted to maintain the substantial horizontality and equilibrium of the closure structure and to guide it upon and support it in respect of the center column and independently of the shell, said guide-members being located outside of and above the gas-space and accessible from the upper side of the closure structure without communication with the gas-space; the sealing means between the closure structure and the shell and column comprising substantially continuous contact members and a mobile sealing medium and means for supplying such medium at the sliding surfaces of the closure structure; and means for supplementally sealing the closure structure centrally at the bottom of its travel, to permit detachment of the contact member around the center column without discharging the gas-space under the closure structure.
- 40 19. In a waterless gas holder, the combination of a shell; a piston-like closure therefor; at least one vertically disposed column within the shell, said column passing through the closure; means for effecting a seal between said column and the closure; a fluid sealing means between the shell and the closure; means for conducting sealing fluid to the column; and means for gathering fluid from the column and conducting the same to the sealing means.
- 45 20. A waterless gas holder as set forth in claim 19, wherein the fluid sealing means is caused to flow exteriorly of the column over the guiding portion thereof.
- 50 21. In a waterless gas holder, the combination of a shell; a piston-like closure therein; means for sealing the closure with reference to the shell; a tank carried by the shell; a fixed column extending upwardly through the tank; a series of shoes bearing against the column at a point within the lower portion of the tank; means for urging said shoes into facewise contact with the column; and means for supplying a sealing medium to the tank.
- 55 22. In a waterless gas holder, the combination of a shell; a piston-like closure therefor; at least one vertically disposed column within the shell, said column passing through the closure; means for effecting a seal between said column and the closure; a fluid sealing means between the shell and the closure; means for conducting

5 sealing fluid to the upper portion of the column; a reservoir carried by the closure for gathering such fluid as it flows down the column; and at least one conduit extending from the reservoir to the means for effecting the seal between the closure and the shell.

10 23. In a gas holder, a holder shell of the type employing therein a vertically translatable piston in sealing engagement with the wall thereof, said shell comprising a framework, plates arranged on the inner surfaces of the framework to form the shell proper, said plates initially positioned and supported on the framework for constituting the shell wall by means of pegs, said pegs integrated with the plates and engaged through the framework, and welds integrating the peg supported and positioned plates with the framework.

15 24. In a gas holder, a holder shell, said shell adapted to receive a piston vertically translatable therein in sealing engagement with the wall thereof, said shell comprising a framework and plates arranged on the inner surfaces of the framework to form the shell proper, said plates including studs projecting outwardly therefrom through the elements of the framework and having heads on their exterior ends for preventing

inward displacement of the plates and holding the same tightly against the framework, said studs initially placed through the elements and the margins of the plates and integrated with the plates, and means sealing the joints of the 5 plates with the framework.

20 25. In a gas holder a holder shell of the type employing therein a vertically translatable piston in sealing engagement with the wall thereof, said shell comprising frame elements of upright beam columns having flanges disposed with their inner surfaces aligned circumferentially, plates arranged on the inner surfaces of the frame elements to form the shell proper, means for securing the plates to the frame elements, 15 said means being comprised both of sparsely distributed securing means comprising widely spaced rivets and of continuous marginal securing means comprising welds substantially completely securing the plates along and about the various 20 edges and marginal portions of the parts constituting the shell wall, said rivets integrated with said plates and engaged through the frame elements, and said welds integrating the rivet supported and positioned plates with the frame 25 elements and with each other.

JOHN A. MASON.
